[57] CLAIM

The ornamental design for a serving dish, substantially as shown and described.

DESCRIPTION

FIG. 1 is a top perspective view of a serving dish showing our new design;
 FIG. 2 is a side elevational view thereof;
 FIG. 3 is an end elevational view thereof;
 FIG. 4 is a top plan view thereof;
 FIG. 5 is a cross-sectional view thereof taken along line 5—5 of FIG. 4;
 FIG. 6 is a partially exploded top perspective view thereof;
 FIG. 7 is an exploded perspective view thereof;
 FIG. 8 is an exploded end elevational view thereof;
 FIG. 9 is an exploded side elevational view thereof;
 FIG. 10 is a top plan view of the container portion of the serving dish;
 FIG. 11 is a bottom plan view of the container portion;
 FIG. 12 is a top plan view of the colander portion of the serving dish;
 FIG. 13 is a bottom plan view of the colander portion;
 FIG. 14 is a bottom plan view of the cover portion of the serving dish;
 FIG. 15 is a top plan view of the divider portion of the serving dish; and
 FIG. 16 is a bottom plan view of the divider portion.
